United States Patent Office.

WILLIAM SLOAN, OF HIGHLAND, IOWA.

Letters Patent No. 65,700, dated June 11, 1867.

IMPROVEMENT IN SLEIGH-BRAKE.

The Schedule referred to in these Letters Patent and making part of the same.

TO ALL WHOM IT MAY CONCERN:

Be it known that I, WILLIAM SLOAN, of Highland, in the county of Clayton, and State of Iowa, have invented a new and improved Sleigh-Brake; and I do hereby declare that the following is a full, clear, and exact description thereof, which will enable others skilled in the art to make and use the same, reference being had to the accompanying drawings, forming part of this specification, in which—

Figure 1 is a side view of a sleigh with my improved brake attached.

Figure 2 is a rear end view of one runner of the same.

Similar letters of reference indicate like parts.

My invention consists in an improved brake for sleighs, constructed, arranged, and operated as hereinafter more fully described.

A is the runner; B are the knees; C are the beams, and D is the rave of the sleigh, about the construction of which parts there is nothing new. E are the jaws of the brake, which are pivoted to the runner about an inch below the upper edge of said runner by a pin or bolt passing through them and through the runner. The jaws E are of such a length, that when turned down their lower ends or points should project about an inch and a half below the face or lower edge of the runner. At or a little above the pivoting-pin, the upper ends of the jaws E are bent at right angles to their former course, as shown in fig. 1; they are then again bent at right angles, and pass towards each other, meeting and being united into a single shaft or stem directly above the upper edge of the runner A, forming a rectangular loop, to allow the jaws to have sufficient play, and so that the said loop may pass down over the rear end of the runner A when the brake is attached to said runner near its end. F is a handle, formed upon or attached to the jaws E at or a little above their point of meeting, as shown in the drawings. The handle F may pass up through a slot formed in the rave D, or it may be bent to one side and pass up through a slot formed in the rear end of said rave D, near its outer edge. This latter construction I prefer, as it brings the handle F more out of the way of the load placed upon the sleigh. G is a prong or arm, attached to the jaws E at or a little above their point of meeting, for the purpose of preventing the jaws E from being turned down farther than to bring the said jaws into a position at right angles to the direction of the runner A. The arm G should be a little longer than the jaws E, so as to strike the ground before the jaws have quite reached a direction at right angles to the direction of the runner, and it should be turned or set back as shown in fig. 1, so as to readily pass over any limb, stone, or other obstruction that may be in the road. H is a spring attached to the under side of the rave D, near the slot, so as to press against the handle F, and hold the brake securely in place when unlocked. The position shown in the drawings is the most convenient one for the brake when the sleigh is used for drawing cord-wood, or other things placed across the sleigh. But when the loading is placed lengthwise of the sleigh, or when a box is placed upon it, it may be more convenient to place the brake further forward, with the handle passing up through a slot formed between the beams C, as shown in dotted lines in fig. 1. In this case the arm G need not be used. The handle F may be made straight, as shown in figs. 1 and 2, or it may be bent at right angles at the upper surface of the rave D, so that when the brake is locked it may lie along the upper side of said rave. In this case the spring H will not be required, since when unlocked the weight of the handle will be sufficient to hold the brake in place. The handle F may be made solid with the jaws E, or it may be made detachable by being inserted in links or rings attached to or in a socket formed in the stem of the jaws E where they meet. This construction enables the handle to be removed for convenience in loading or unloading the sleigh.

What I claim as new, and desire to secure by Letters Patent, is—

1. The jaws E, pivoted to and straddling the runner A, prong G, and handle F, when constructed and arranged as herein set forth for the purpose specified.
2. Attaching an arm or prong, G, to the brake E F, substantially as herein shown and described, and for the purpose set forth.

WILLIAM SLOAN.
